CARRIER FOR PIES OR THE LIKE

William Swanson, 114 W. Rock, Plano, Ill.

Filed Apr. 15, 1959, Ser. No. 55,517

Term of patent 14 years

(Cl. D58—5)

FIG. 1.

FIG. 2.

FIG. 3.

FIG. 4.

I claim:

The ornamental design for a carrier for pies or the like, as shown and described.
